No. 36,720.

Patented December 29, 1903.

UNITED STATES PATENT OFFICE.

ISIDORE LEROY, OF PARIS, FRANCE, ASSIGNOR TO SOCIÉTÉ ISIDORE LEROY
ET FILS, OF PARIS, FRANCE.

DESIGN FOR WALL-PAPER.

SPECIFICATION forming part of Design No. 36,720, dated December 29, 1903.

Application filed November 20, 1903. Serial No. 182,025. Term of patent 14 years.

To all whom it may concern:

Be it known that I, ISIDORE LEROY, a citizen of the Republic of France, and a resident of Paris, France, have invented a new, original, and ornamental Design for Wall-Paper and the Like.

The new design for wall-paper and the like is shown in plan in the accompanying drawing.

What I claim as new is—

The ornamental design for wall-paper, as shown.

ISIDORE LEROY.
